ABSTRACT OF THE DISCLOSURE

A process for filling a bottle or can with a beverage, particularly beer, including the step of washing the container, introducing nitrogen gas into the container simultaneously with washing water used in the washing step, and displacing the nitrogen by introducing the beverage into the container.

This application is a continuation-in-part of United States application Ser. No. 500,154, filed Oct. 21, 1965.

BACKGROUND OF THE INVENTION

In a known process for filling beverage into containers, the air in the container is evacuated and thereafter nitrogen gas is introduced into the container. Alternatively, the air may be flushed out of the container by rinsing out the container with nitrogen gas. These known processes are complicated, and the nitrogen gas introduced into the container is easily contaminated by air left behind in the container or by air which is drawn into the container by the nitrogen flow thereinto.

In processes where the container is rinsed with nitrogen to remove the air, a relatively long rinsing time is necessary and a large quantity of nitrogen gas is required to fill the container with nitrogen with a purity of at least 98%. In this connection, it should be noted that when the container is filled with pure nitrogen, any oxygen which may be dissolved in the beverage is withdrawn from the beverage; in contrast, when filling with impure nitrogen, the impure nitrogen gas only prevents air from entering the container during the introduction of the beverage, but does not affect the oxygen dissolved in the beverage. In the known processes, it is not possible to introduce pure nitrogen into the container during the short time interval which exists in the mechanical bottling processes between the washing of the container and filling with the beverage.

It is an object of the invention to remove the disadvantages of the known method for filling bottles or cans with a beverage.

SUMMARY OF THE INVENTION

According to the present invention, there is provided a process for filling a container with a beverage, which process comprises the steps of washing the container, introducing nitrogen into the container simultaneously with the washing water used in said washing step, and displacing the nitrogen by introducing the beverage into the container.

In this manner, the free air present in the bottle is driven out and also the oxygen dissolved in the washing water is liberated by the interaction with the nitrogen gas and then driven out so that the bottle after the washing is filled with nitrogen gas and possibly minute amounts of wash water with a very low oxygen percentage.

According to another feature of the invention, the bottle is washed with nitrogen immediately preceding the filling. The container is preferably a bottle or can while the

2

beverage is preferably beer. The nitrogen gas may be introduced into the container in various ways, for example, centrally through a spraying nozzle and surrounded by an annular stream of washing water delivered by the same nozzle. Preferably, the nitrogen gas is held, according to a following feature of the invention, at an over-pressure in the bottle or the can, and driven out by the beverage pouring in during the filling. As a result, the oxygen which might be dissolved in the beer is liberated by the interaction between the beer pouring in in a thin film along the bottle wall, according to a known process, and then driven out together with the nitrogen gas.

According to a known process for filling bottles or cans with beverages, the beverage is allowed to flow from a filling container in the filling machine to the lower-positioned bottle or can by gravity.

According to a feature of the invention, only, or substantially only, nitrogen gas is present over the beverage in the filling container. The beverage may be pressed from the container by the pressure of the nitrogen gas, so that the beverage neither in the storage containers, nor during the storing up in the bottles or the cans has the opportunity to pick up oxygen. The nitrogen gas driven away during the filling may be removed in various manners.

According to another feature of the invention, the nitrogen gas is forced from the bottle or the can to be filled to the gas supply container of the filling machine during the filling step.

A bottle filled in accordance with the invention may be closed simply or after a foam generation in the bottle neck in which latter event the beer is stored with an extremely low oxygen content.

BRIEF DESCRIPTION OF THE DRAWING

FIG. 1 diagrammatically discloses apparatus for the simultaneous introduction of wash water and an inert gas into the beverage container;

FIG. 2 is a side view of the apparatus of FIG. 1; and

FIG. 3 is a cross-sectional view of apparatus including a nozzle adapted for simultaneously introducing wash water and an inert gas into each beverage container.

DETAILED DESCRIPTION OF THE INVENTION

FIGS. 1 and 2 illustrate apparatus which may be used for the introduction of wash water and an inert gas simultaneously into each bottle or container for the beverage. It should be understood that the gas which is to be used must be one which contains substantially no free oxygen, and preferably the gas used is nitrogen. FIG. 1 shows two rows of bottles 1 which are placed upside down over respective spraying nozzles 2 of a bottle-washing machine during the bottle-washing operation. The side view of FIG. 2 further illustrates each bottle which has been positioned above a respective one of the spray nozzles 2.

FIG. 3 is a vertical sectional view of a spraying nozzle 2 together with a portion of a bottle 1 which is placed upside down above the nozzle during the washing operation. Each nozzle is provided with a central opening 11 for introducing nitrogen gas into the bottle 1 from a source of nitrogen gas designated by the reference numeral 8. The spraying nozzle 11 is surrounded by an annular spraying nozzle 9 by means of which the wash water which is supplied to the nozzle at 10 may be sprayed into the interior of the bottle 1.

For the arrangement shown in FIG. 1, the wash water is introduced into the conduits 4, each of which fits a plurality of nozzles 2. Disposed between the conduits 4 is a single conduit 6 which supplies nitrogen gas to both of the rows of spraying nozzles, the nitrogen gas being

supplied from the conduit 6 to the individual nozzles 2 by means of flexible tubes 7.

During the washing operation, each bottle is thoroughly washed by the wash water entering into the inverted bottle from the nozzle 2, and at the same time is filled with a quantity of nitrogen gas. Any oxygen remaining in the bottle is substantially entirely removed from the bottle during this process. When the bottle is removed from a position directly above the nozzle, or when the supply of wash water is cut off, the wash water remaining in the bottle runs out by gravity, but the nitrogen stays inside because of its having a lower specific gravity than the surrounding air. Subsequently, the bottle is inverted to an upright position and filled with the beverage which displaces the nitrogen then occupying the bottle. Preferably, this filling operation takes place in a nitrogen atmosphere, so that the beverage does not in any way come into contact with oxygen during the filling operation.

The process of this invention is not limited to the filling of containers such as bottles or cans with beer, but may also be applied to the filling of containers with other beverages whether or not containing carbon dioxide and whether or not containing alcohol.

What I claim is:

1. A process for filling a container with a beverage comprising the steps of, thoroughly washing the container with washing water, introducing nitrogen gas into the container simultaneously with the washing water while the container is in an inverted position, permitting the washing water to drain from the inverted container while the nitrogen gas remains therein because of its specific gravity being less than that of air, inverting said container to its upright position and 35 filling said container with the beverage,

the filling operation being carried out in an atmosphere of nitrogen gas to prevent contact of the beverage with oxygen during the filling operation.

2. A process for filling a container with a beverage which comprises the steps of, thoroughly washing the container with wash water introduced in the form of an annular stream, introducing into the container simultaneously with the wash water, and while said container is inverted, nitrogen gas, said nitrogen gas being introduced as a jet internally of the annular stream of wash water, and while said container is positioned upright introducing the beverage into the container to thereby fill the container and concurrently displace the nitrogen gas.
